UNITED STATES PATENT OFFICE

FRANCIS M. CASE, OF CLEVELAND HEIGHTS, OHIO, ASSIGNOR TO CLAUDE O. HARMON,
OF CLEVELAND, OHIO

SHARPENING ATTACHMENT FOR DISK HARROWS

Application filed September 13, 1926, Serial No. 135,070. Renewed May 23, 1931.

This invention relates to sharpening attachments for disk harrows and is more particularly directed to a sharpening device which may be supported so as to engage the disk of a harrow to sharpen the same while the harrow is in operation.

One object of the invention resides in the feature of providing a supporting means for the sharpening device upon which the latter is adjustably mounted so that it may be moved from one disk to the next of any one in a line without removing the sharpening device from the support.

Another object of the invention is to provide a sharpening device which when positioned adjacent one of said disks is maintained in cutting or sharpening engagement by means of an adjustable tension member which forms a part of the sharpening device.

Other objects of the invention are to provide a sharpening device which may be transferred from one gang of disks of a harrow to another gang of disks of the harrow, where the convex surfaces of the disks of each gang are opposite to each other, by merely removing the sharpening device from the support of one gang and reversing it on a supporting means of the adjacent gang of disks.

A further object of the invention resides in the provision of a means upon the sharpening device for positioning the cutter with respect to the edge of the disk to be sharpened so that this cutter may be radially adjusted depending upon the direction in which the convex surface extends and the direction of rotation of the disks.

A still further object resides in a means for securely positioning and mounting the supporting means with respect to the hub of the gang of disks so as to prevent the sharpening device if becoming loosened, from dropping down onto the cutting edge of the disks.

With the objects above indicated and other objects hereinafter explained in view my invention consists in the construction and combination of elements hereinafter described and claimed.

Referring to the drawings:

Fig. 1 is a cross sectional view taken on line 1—1 of Fig. 6 showing the position and arrangement of the attachment with respect to the disks of the harrow.

Fig. 2 is a horizontal cross sectional view on line 2—2 of Fig. 1 showing the relative position of the cutter with respect to the cutting edge of the disk with the yoke in section.

Fig. 3 is a top plan view of Fig. 2 showing the reversible feature of the yoke.

Fig. 4 is an end view looking toward the disk in Fig. 2.

Fig. 5 is a top plan view similar to Fig. 2 but showing the sharpening device in the position it assumes when being transferred from one disk to another, the line A—A representing the extremities of the peripheries of a gang of disks.

Fig. 6 is a rear end view of a gang of disks showing the supporting means for the guide bar and the sharpening device positioned with respect to one of the disks.

Fig. 7 is a segmentary view showing a modified form of the supporting and spacing arm engaging the hub of the disk.

Fig. 8 is a segmentary view showing a further modified form to that shown in Fig. 7.

Fig. 9 is a modified form of sharpening device whereby a sharpening wheel has been substituted in place of the cutter, and

Fig. 10 is a top plan view of the arrangement shown in Fig. 9.

In the drawings, 1 indicates one of the disks of a gang and 2 represents the usual hub connection between the disks 1, these disks and hubs being secured together in any suitable means, one form of means being a square bolt extending entirely through the hub and disks as indicated at 3 in Fig. 1. As shown in Fig. 6, 4 indicates bearings positioned around the hubs between the end disks of the gang and extending upwardly from these bearings 4 are arms 5 adjustably mounted therein, the upper ends of which are riveted to a cross bar 6 usually employed as a supporting means for the scrapers of the various disks. This cross bar 6, however, may be any

100

other portion of the harrow which extends adjacent the peripheries of the disks 1.

A guide rail 7 in the form of a T rail extends parallel with the cross bar 6, the web 5 of the T rail extending upwardly and at a slight incline toward the vertical central line of the disks. An arm 8, T-shaped in cross section with the web extending upwardly is provided with a transverse slot 9 at one end 10 engaging with the web of the guide rail 7 and is adjustably mounted thereon and secured thereto by means of a set screw 10 extending through an opening in the end of the arm into engagement with the web of the guide 15 rail 7. Directly above the transverse slot 9 and transversely thereof is an arcuate flange or rim 11 formed integral with the web of the arm 8, a cross section of which is T-shaped. A supporting bracket 12 is provided 20 with a right angled extension 13 through which extends a T slot adjustably engaging the arcuate flange 11 of the arm 8. This supporting arm 12 is maintained in adjusted position by means of a set screw 13a 25 extending through the T slot of the right angled extension 13 and into engagement with the periphery of the arcuate flange 11. A hook bolt 14 extends through one of a plurality of openings 15 in the supporting arm 30 12, the hooked portion engaging the lower end of the cross bar 6 and is held in engagement therewith by means of a nut engaging the screw threaded end extending beyond the supporting arm 12.

35 The opposite end of the arm 8 extends at a downward angle and inwardly toward the horizontal center of the disks and has slidably mounted thereon a bracket 16 which is provided with a T slot adapted to engage the T head of the arm 8. A depending arm 17 is formed integral with the bracket 16 and extends downwardly and under a portion of the hub 3. The bracket 16 on the arm 8 is adjustably secured through a set screw 18 extending 40 through the bracket 16 into the slot and into engagement with the head of the arm 8. By this adjustment the guide rail 7 may be securely and correctly positioned with respect to the peripheries of the disks 1 45 so that the sharpening device is correctly positioned along the cutting edge of the disk 1 while the same is being sharpened.

It is sometimes desirable to prevent the possibility of the arm 8 being pulled away 50 from the hub 3 and in such a case the bracket 18 may be made in the form shown in either Figs. 7 or 8.

A yoke 19 is provided with a pair of transverse slots 20 one of which engages the head 55 of the guide rail 7, these slots being positioned on each side of the horizontal center of the bracket and extend at opposite angles so that the bracket may be reversed on the guide rail 7 at will, depending, of course, 60 upon the direction in which the convex sur-

faces of the disks 1 extend. A bell crank 21 is pivotally mounted within the yoke 19 by means of a pin 22 extending through the arms of the yoke and the bearing of the bell crank. One arm 21a of the bell crank 21 is provided with a bifurcated end 23 which receives one end of an eye bolt 24, the ends being pivotally secured together by means of a pin 25. This eye bolt 24 extends through a slot 26 provided in an extension 27 formed integrally with the yoke 19 and a washer 28 engages the extension 27 and acts as a seat for the spring 29 disposed upon the body of the eye bolt 24. The opposite end of the eye bolt 24 is screw threaded and receives a wing nut 30 which engages with the end of the spring 29, the turning of the wing nut 30 adjusting the tension of the spring 29.

The other arm 21b of the bell crank 21 is formed to receive the cutting tool 31. This cutting tool 31 is seated in a semi-circular groove 32 which is formed on the inner side of the arm and extends throughout the length. An eye bolt 33 is provided with a squared opening 34 which receives the cutting tool 31, the body of the eye bolt 33 extending through a slotted opening 35 in the arm of the bell crank 21 transversely of the slot 32. The opposite end of the eye bolt 33 is provided with screw threads 36 which receive a wing nut 37, the tightening of which secures the cutting tool 31 within the groove 32. The outer surface of the arm 21b of the bell crank 21, adjacent the slot 35, is provided with diverging tapered surfaces 39 and a washer 38 is interposed between the tapered surfaces 39 and the wing nut 37. Upon the tightening of the wing nut 37 the washer 38 may be brought into contact with either of the tapered surfaces 39 which thereby determines the angular position of the cutting tool 31, this angular position depending upon the direction in which the convex surfaces of the disks 1 extend. The slot 32 extends throughout the inner surface of the arm 21b of the bell crank 21 so that the cutting tool 31 may be shifted longitudinally to utilize the entire cutting surface thereof.

It is sometimes desirable to construct a supporting arm such as indicated at 8 which will prevent accidental longitudinal movement of the same, after it has once been properly located and secured with respect to the guide rail 7. Two constructions are shown clearly in Figs. 7 and 8 wherein, in Fig. 7, the supporting arm 8 is formed of a T section with the head of the section extending downwardly. This T section slidably receives a bracket 40 provided with a T shaped slot adapted to engage the head of the supporting arm 8 and is secured in an adjustable position by means of a set screw 41. A U-shaped portion 42 substantially surrounds the hub 3 and is integrally formed with the bracket 40, the depending arms of the U- 130

shaped portion 42 extending far enough downwardly beyond the horizontal center of the hub 3 to prevent longitudinal movement of the bracket 40 when once secured in the proper position.

In Fig. 8 the supporting arm 8 is formed of a T section and has slidably mounted thereon a pair of brackets 43 provided with T shaped slots adapted to engage the head of the supporting arm 8. These brackets 43 are secured in the desired position by means of set screws 44 and the brackets are provided with converging, depending arms 45 which project downwardly substantially below the hub 3 and inclose proximity thereto. This construction also prevents appreciable longitudinal movement of the supporting arm 8 so that the T rail 7 when once properly located is maintained in this proper position.

It is sometimes further desirable to employ a grinder in preference to the cutter 31 which has been heretofore described. This modification is clearly disclosed in Figs. 9 and 10. The construction of the yoke and its associated parts are substantially the same as the yoke 19 heretofore described except that the tool holder arm 21b of the bell crank 21 is omitted and the arm 46 substituted therefor. This arm 46 forms one arm of the bell crank 21 and is provided with a head or enlarged circular portion 47 which has a central bore 48. A bushing 49 closed at one end is positioned in the opening 48 and frictionally secured therein and positioned by means of an annular flange 50 engaging with the inner surface of the head 47. The grinding wheel 51 of proper diameter has a counterbore 52 in its upper surface and a central opening 53 extends through the grinding wheel 51. This central opening 53 receives a bushing 54 and a stub shaft 55 is securely fastened to the under side of the grinding wheel 51 by means of a bolt 56 extending through the bushing 53 and into a centrally disposed screw threaded opening in the end of the stub shaft 55. The outside diameter of the stub shaft 55 is less than the inside of the diameter of the bushing 49 so that the stub shaft 55 may easily rotate within the bushing. A thrust bearing or ball 57 is pocketed within the end of the bushing 49 and engages with the lower end of the stub shaft 55 and functions to permit the grinding wheel 51 to freely rotate.

Fig. 6 clearly shows the relative position of the various parts of the supporting means and cutting device, the cutting device being in engagement with one of the disks 1 of a gang. When it is desirous to sharpen the cutting edge of the disks 1, referring particularly to Fig. 1, the sharpening attachment is positioned as shown therein and the eye bolt 33 carrying the cutter 31 is shifted radially downwardly onto the lower diverging portion 39 of the arm 21b. This po-

sitions the cutting edge of the cutter 31 at a slight angle with respect to the cutting edge of the disk 1 so that rotation of the disk, in a counterclockwise direction, causes the cutting edge thereof to be engaged by the lower inner edge of the cutter 31 thereby producing a shear cut on the cutting edge of the disk 1.

The tension of the cutter 31 upon the disk 1 is regulated through the tension spring 29, the tightening of the wing nut 30 increasing the tension of the cutter 31 on the disk 1 and the unscrewing or loosening of the wing nut 30 releasing the tension on the spring 29 and subsequently affecting the tension between the cutter 31 and the disk 1. When one of the disks 1 has been sharpened and it is desirous to sharpen the adjacent disk or any other disk in the gang, the wing nut 30 is loosened to an extent to permit the washer 28, around the eye bolt 23, to be swung beyond the end of the extension 27 and out of the slot 26. This permits the sharpening device to be positioned as indicated in Fig. 5 and slid along the guide rail 7 passing the outer peripheries of the disks 1 which is indicated by line A—A of Fig. 5. When the sharpening device has been moved along the guide rail 7 to a position adjacent the disk to be sharpened the eye bolt 23 is swung back into the slot 26 of the extension 27 and the washer 28 is again adapted to engage the rear surface of the extension 27. This positions the cutter 31 in substantially the same position as indicated in Fig. 2 and the tension of the cutter 31 against the disks 1 can be adjusted by means of the wing nut 30 as has been heretofore described.

The positioning and the adjustment of the grinding wheel 51 and the tension of the grinding wheel 51 against the disk 1 is regulated in the same manner as has been heretofore described. The tension of the grinding wheel 51 against the cutting edge of the disk 1 is increased by turning the wing nut 30 downwardly thereby increasing tension of the spring 29 and to relieve the tension between the grinding wheel 51 and the disk 1 the direction of rotation of the wing nut is reversed. The sharpening device is adjusted from one disk to another in the same fashion as that described with respect to Fig. 5.

On most of the disk harrows one gang of disks is positioned as in Fig. 6 with the convex surfaces of the disks 1 extending in the same direction, but the adjacent gang of disks is usually positioned with the convex surfaces of the disks extending in the opposite direction. A supporting rail 7 is supported by the same apparatus as has been heretofore described, but of course is supported adjacent the adjacent gang of disks. As it is necessary to sharpen the edges of the disks of the adjacent gang where the disks are arranged oppositely to those shown in

Fig. 6, it is necessary to remove the yoke 19 from the guide rail 7 and to support the yoke 19 on the opposite rail and from the opposite slot 20 of the yoke. It should be noted that 5 this reverses the position of the cutting edge on the disk and in order to attain the proper shearing cut the wing nut 37 is loosened and the eye bolt 33 is swung laterally so that the washer 38 engages the opposite diverging 10 surface 39 thereby swinging the cutter 31 around until the proper edge engages with the cutting surface of the disk 1. It is also necessary to remove the set screw 58 which secured the yoke 19 to the guide rail 7 as 15 shown in Fig. 1 and to place it in the screw threaded opening directly opposite thereto thereby securing the sharpening device in its reversed position on the rail 7 of the adjacent gang.

20 Having thus described my invention, what I claim is:

1. A sharpening attachment for disk harrows comprising a guide bar extending transversely of the disks, means for adjustably 25 mounting said guide bar on a portion of a harrow, a supporting member adjustably mounted on said guide bar and provided with a pivotal tool holder, a cutting tool mounted for angular adjustment around its longitudinal axis in said tool holder and adapted 30 to engage a disk to sharpen the same, and a tension regulating device engaging the supporting member and the tool holder to maintain the proper tension between the cutting 35 tool and the disk.

2. A sharpening attachment for disk harrows comprising a guide bar adapted to be mounted on a portion of the harrow and extending at right angles to the disks, means for 40 adjusting said guide bar with respect to the peripheries of said disks, a supporting member slidably mounted on said guide bar, said member having a pivotal tool holder, a cutting tool adjustably mounted in said tool 45 holder and adapted to engage the disk to sharpen the same, and pressure exerting means attached to the supporting member and the tool holder for creating pressure of the cutting tool on said disk.

50 3. A sharpening device for disk harrows comprising a yoke provided with a groove adapted to slidably engage a portion of said harrow, extending axially along the disk gang 55 a pivoted tool holder secured to said yoke, cutting means carried by the said tool holder, and a tension means attached to the yoke and the tool holder.

4. A sharpening device for disk harrows 60 comprising a yoke provided with oppositely disposed grooves adapted to slidably engage a portion of said harrow, a bell crank pivoted to the yoke, one arm serving as a tool holder, a cutting tool adjustably mounted in said arm, 65 and a tension spring attached to the other

arm of the bell crank and to a portion of the yoke.

5. A sharpening device for disk harrows comprising a yoke provided with a pair of oppositely disposed grooves, adapted to slidably engage a portion of said harrow, a bell crank pivoted to the yoke, one arm serving as a tool holder, a cutting tool mounted in said arm and adapted for angular movement, a bolt pivotally secured to the end of the opposite arm of the bell crank having the other end removably engaging the yoke, a spring surrounding the bolt and engaging the yoke, and a means engaging the bolt for adjusting the tension of the spring. 70 75 80

6. A sharpening device for disk harrows comprising a yoke provided with a pair of oppositely disposed grooves for positioning the device with respect to the disks, a cutter holder pivoted to the yoke, a tension adjusting device mounted between the yoke and the cutter holder, a cutting tool mounted for longitudinal adjustment in the cutter holder, and means for angularly adjusting the cutting tool for properly positioning the tool 85 with respect to the disk. 90

7. A sharpening device for disk harrows comprising a yoke provided with a pair of oppositely disposed grooves for positioning the device with respect to the edge of the 95 disk to be sharpened, a cutter holder pivoted to the yoke, a tension device attached to the yoke and the cutter holder, a cutting tool mounted in the cutter holder, and means for angularly adjusting the cutting tool so as to 100 effect a shear cut on the edge of the disk as it rotates, the adjustment depending upon the slot from which the device is suspended.

8. A sharpening attachment for disk harrows comprising a yoke provided with transverse grooves adapted to slidably engage a portion of said harrow, a tool supporting member pivotally mounted in said yoke, a cutting tool carried by said member and adjustable angularly, resilient means cooperating with said cutting tool, and adjustable means for varying the tension between the cutting tool and the disk. 105 110

9. A sharpening attachment for disk harrows comprising a yoke provided with transverse grooves disposed on opposite sides of the horizontal center adapted to slidably engage a portion of said harrow, a tool supporting member pivotally mounted in said yoke, a sharpening tool carried by said member and adapted for longitudinal and angular adjustment, and resilient means for creating tension between the cutting tool and the disk. 115 120

10. A sharpening attachment for disk harrows comprising a yoke provided with oppositely disposed grooves extending angularly with respect to the horizontal center thereof, adapted to slidably engage a portion of said harrow, a tool supporting member pivot- 125 130

ed within said yoke, a sharpening tool longitudinally mounted in said member, means for angularly adjusting the sharpening tool, and an adjustable tension means secured to the tool supporting member and engaging said yoke for varying the tension between the sharpening tool and the disk.

11. A sharpening attachment for disk harrows comprising a guide bar, adjustable means secured to the guide bar and to a portion between the disks for positioning the guide bar with respect to the periphery of the disks, adjustable means attached to the first mentioned means and to a portion of the harrow for supporting the guide bar, a supporting member slidably mounted on the guide bar, a tool holder in the form of a bell crank pivoted at its central portion to the supporting member, a recess formed in one arm of the tool holder, a cutting tool longitudinally mounted in said recess, said tool being secured in position by means of an eye bolt through which the cutting tool extends, the body of the bolt being mounted for angular adjustment in the arm and means attached to the opposite arm of the bell crank adapted to engage a portion of the supporting member for adjusting the tension between the cutter and the disk.

12. A sharpening device for disk harrows comprising a guide bar adapted to be attached to said harrow, a yoke provided with oppositely disposed grooves suspended from said guide bar depending upon the direction in which the convex surface of the disks extend, means for locking the yoke to the guide bar, a tool holder pivotally mounted in said yoke provided with a longitudinal groove adapted to receive and support a cutting tool, a cutting tool positioned in said slot and extending through an opening in an eye bolt, the opening substantially conforming to the cross section of the cutter, and the body of the eye bolt extending through an opening transversely of said groove, and adapted for angular adjustment, and means attached to the opposite portion of the tool holder engaging a portion of the yoke, said means being provided with a resilient member for regulating the tension between the cutter and the disk.

In testimony whereof, I hereunto affix my signature.

FRANCIS M. CASE.
